F. F. OAKLEY.

EXTENSION REEL FOR ELECTRIC LAMPS, PORTABLE DRILLS, AND THE LIKE,
APPLICATION FILED DEC. 4, 1919.

1,362,344.

Patented Dec. 14, 1920.

Inventor:
Fred F. Oakley,
By John Elias Jones,
Attorney.

UNITED STATES PATENT OFFICE.

FRED F. OAKLEY, OF CINCINNATI, OHIO, ASSIGNOR TO THE CINCINNATI SPECIALTY MANUFACTURING COMPANY, OF CINCINNATI, OHIO, A CORPORATION OF OHIO.

EXTENSION-REEL FOR ELECTRIC LAMPS, PORTABLE DRILLS, AND THE LIKE.

1,362,344.

Specification of Letters Patent. Patented Dec. 14, 1920.

Application filed December 4, 1919. Serial No. 342,497.

To all whom it may concern:

Be it known that I, FRED F. OAKLEY, a citizen of the United States, and a resident of Cincinnati, in the county of Hamilton and State of Ohio, have invented a certain new and useful Improvement in Extension-Reels for Electric Lamps, Portable Drills, and the like, of which the following is a specification.

This invention relates more particularly to the self-winding reels, as well as to an important improvement in the type of reels heretofore patented by Adam Heim October 12, 1915 and January 30, 1917, No. 1,156,402 and No. 1,214,031, respectively and assigned to the same assignee, The Cincinnati Specialty Manufacturing Company, as the one herein, and its principal object is to provide the said peculiar type of reels with an automatic circuit-breaker or switch that is mounted directly on the reel bearing-support so that a safety-contact for the lighting of the lamp shall be effected while the latter is in actual illuminating use or service and then an instant breaking or parting of said contact effected when the lamp-cord is wound on the reel, whereby the lamp is in normal resting position and without any energizing current present therein nor in the reel itself and whereby key-sockets are dispensed with for the removable lamps and to entirely free the resting lamp from current to meet the very strict requirements of insurance underwriters as well as to reduce danger from charged wires heretofore resulting in damaging fires and bodily injury.

The details of structure will be fully described in connection with the accompanying sheet of drawings, in which—

Figure 1 is a side elevation showing the device in normal position, with the circuit broken and the lamp "reeled up" out of illuminating or current-charged use; Fig. 2, a fore-end elevation showing the left-hand side of the device and its closure-cap in section; Fig. 3, a detail perspective view of the said closure-cap; Fig. 4, a detached perspective view of the safety bridge or resilient contact-arm of the circuit-breaker device embodying one of the members of my improvement herein; Fig. 5, a detached perspective view of the lower contact stop or post-plate of said circuit-breaker device; and Fig. 6, a vertical section of the spring-controlled reel, including a diagrammatic

elevation of the forked bearing-support, the circuit-breaker devices in duplicate thereon and the box or casing on the reel-shaft for containing the contacts and circuit-connections leading to and from the lamp-cord. (The cover or cap plates for the circuit-breakers, and the upper part of the fork and wires are omitted in this view.)

1 indicates the circumferentially-grooved reel or wheel on which the lamp-cord 2 is self-wound under spring-tension and from which, also, it is unwound to the desired using or service point of the lamp itself (not shown) that is removably-mounted, as customary, in the socket 3, the latter, in turn, having a convenient hand-grasp 4, and a stop 5 being adjustably-mounted on the said lamp-cord for determining and limiting its return-winding as well as automatically breaking the light-circuit when the lamp is not used and in the manner I shall now proceed to describe.

6 indicates a swivel-head by which the reel device is suspended from the ceiling tripod-bracket 6^a.

7 indicates each of a spaced pair of pendent metal arms forming a forked or open bearing support for the intermediate reel 1, the latter being mounted on the transverse shaft 8 that is detachably-secured by means of cotter-pins 9.

10 is a strip of insulating material on the outer face of each of the pendent arms 7, ordinarily reaching from top to bottom thereof, but it may, if desired, (but not shown) terminate just above the axis 8 of the reel.

11, 11^a indicate, respectively a pair of insulated current intake or feed and outlet wires leading from and to the source of supply into the swivel-head 6 and thence each extending outwardly at 12 and 12^a for the usual bared loop-connection 13 with a binding-post 14 that projects outwardly from the insulated face of the pendent arm 7. Nuts 15 and 16 are placed at the back and front of the bared loop-connection 13, and the upper, flat eye-end 17 of a resilient, somewhat flexed or sloping conductor bridge or arm 18 is first inserted on the said binding-post 14, then the inner nut 15, then the loop-connection 13 and, finally, the outer nut 16. The arm 18 is of flat metal and its lower free end rests normally out of electric contact with a stop or post-plate 19, the

latter projecting upwardly from a flat eye-end 20, which, in turn, is inserted over a lower terminal screw-bolt post 21. The post 21 projects through the pendent arm 7 from 5 an insulated current conductor arm or plate 22 on the inner face of the disk 23, as shown in Fig. 6, the said disk 23 lying adjacent to the said pendent arm 7 and a nut 24 being applied to the outer end of the post 21, after 10 an insulator-washer 25 has been first inserted. The current passes through the plate 22 whose lower end encircles the reel-shaft 8 and thence to the lamp-cord conductors 2^b and thence to the lamp-cord 2, as shown in 15 Fig. 6.

The stop or post-plate 19 is a flat strip of good conductor metal and is bent vertically at 19^a for assuring a full and certain broad surface-contact of the lower flat end of the 20 pendent spring or bridge-arm 18 in closing or establishing circuit for the lamp at the outer end of the cord 2. The periphery of the stationary disk 23 is inwardly-flanged for accommodating the rim of the hollow 25 hub 26 of the reel which rotates therein.

Each of a horizontal pair of flat metal gravitating rock arms or levers 27, 27, that span the reel, is pivotally-mounted at one inner end 28 on a headed pin 29 projecting 30 from the lower end of the pendent arm 7, and another upper inner end 30 of the rock-arm 27 is slotted at 31 to engage a headed pin 32 that projects from the pendent arm 7 at a point just above the contact stop or 35 post-plate 19, as best seen in Fig. 1.

A lateral, outward projection 33 is provided on the extreme end of the member 30 of the rock-arm 27 and carries on its face an insulated button 34 for non-conducting pressure-contact with the face of the 40 resilient bridge-arm 18 when the rock-arm 27 is swung or raised on its pivot 29 to release the lower end of the bridge-arm from contact with the stop or post-plate 19 to 45 completely break electric-circuit from the reel, cord and lamp when the latter is not in active illuminating service or use.

The outer ends 35 of the two pivotal or rock arm members 27 are turned at right-angles inwardly toward each other, as 50 shown in Fig. 2, and duly spaced apart but otherwise connected so as to act in unison by means of a vertical, elongated wire loop 36 through which the lamp-cord extends outwardly from the reel. The upper end 37 of the loop 36 is flared outwardly (Fig. 1) to receive the upward thrust of the adjustable button 5 that is used to limit the return-winding of the lamp-cord on the reel 55 and simultaneously, forcibly and automatically cutting off the current from the lamp by depressing or backing the two bridge-arms 18 from circuit-closing contact with the upright stops or post-plates 19. Nor-

mally, while the circuit is intact to the 65 lamp, the insulator-buttons 34 are not in actual presser-contact with the bridge-arms 18. The weight of the connecting-loop 36 at the outer ends of the rock-arms 27, 27 serves to accelerate the gravitation 70 of the latter on their pivots 29, 29, to hold the insulator-buttons 34 from presser-contact with the bridge-arms 18 when the current is flowing to the lamp through the bridge-arms when closed against the contact post-plates 19. 75

In operation it will be readily seen that the bridge-arms 18, 18 and their contact-releasing and depressing or backing members 30, 30 serve in the capacity of switches 80 at both sides of the reel to break circuit in the circuit-closing devices located at both sides of said reel, simultaneously, and instantly shut off the flow of all current from the source of supply through the reel and 85 lamp-cord to the lamp, making the device at once a thoroughly safe and reliable one to handle, both for extension-lamp service and for portable electric drills, grinders, 90 fans and the like in machine shops, garages and elsewhere, and without the use of a key-socket for the lamp and other utility connections.

A removable closure plate or housing 38 (Fig. 3) is used on each of the two circuit-closing devices herein to cover and protect them at both sides of the reel 1. 95

I claim:—

A safety switch device for use in connection with extension electric-lamp reels, comprising a self-winding reel, intake wires, a pair of reel supporting-arms each having an outer insulated surface, a binding-post at the upper end of each reel supporting-arm, a resilient circuit-closer arm projecting downwardly from said binding-post, a stop or post-plate on said insulated supporting-arm for presser-contact of the lower free end of said resilient closer-arm, a pair of gravitating 100 rock-arms on the said supporting-arms each having a slotted projection at its inner end, insulator presser-buttons on the said slotted projections adapted to forcibly engage or back the resilient circuit-closer arms to 105 break contact with the said stops or post-plates, a loop-member connecting the outer ends of said rock-arms, a lamp-cord for conducting current to and supporting the lamp, and an adjustable stop or button on 110 the lamp-cord adapted to be forcibly drawn into contact with the upper cross-bar of the loop for swinging the rock-arms upwardly when the lamp-cord is released for the automatic return to the reel thereof under the 115 winding-tension of said reel. 120

FRED F. OAKLEY.
